POLYMERIZATION AND CRACKING OF HYDROCARBON GAS-MINERAL OIL SOLUTIONS

Filed June 17, 1935

UNITED STATES PATENT OFFICE

2,177,146

POLYMERIZATION AND CRACKING OF HYDROCARBON GAS-MINERAL OIL SOLUTIONS

Percy A. Maschwitz, Chicago, Ill., assignor to The Pure Oil Company, Chicago, Ill., a corporation of Ohio

Application June 17, 1935, Serial No. 27,011

12 Claims. (Cl. 196—9)

- This invention relates to process and apparatus for simultaneously converting heavy oils or low octane rating naphtha and hydrocarbon gases into high octane rating gasoline. More particularly the invention is concerned with method and apparatus for converting hydrocarbon gases into heavier hydrocarbons under high super-atmospheric pressure without necessitating the use of high pressure compressing equipment.
- It is well known that heavy oils and naphthas may be cracked to form lower boiling hydrocarbons by subjecting them to conditions of high temperature and pressure. Under conditions of the same order, gases containing olefines may be polymerized to hydrocarbons normally liquid. At higher temperature, gases consisting mostly of paraffinic hydrocarbons may be cracked to form olefines, which in turn may be polymerized to form liquid hydrocarbons.

It has been the usual practice in the past to carry out each of these processes separately, and in the case of gases, compressors have been employed for charging the gases under high super-atmospheric pressures, which entails considerable expense.

In my invention it is only necessary to compress the gases to relatively low super-atmospheric pressures in the gaseous phase, at which pressure they can be pumped in the liquid phase at atmospheric temperatures into the processing apparatus at any desired pressure for a fraction of the cost entailed when the gases are charged in the gaseous phase.

One of the objects of this invention is to provide means for charging gases in the liquid phase to a gas conversion process under high pressure, using compressors operating in the gaseous phase merely to secure sufficient pressure to bring the gases into the liquid phase prior to charging them to the conversion system under higher pressures.

Another object of this invention is to provide means to simultaneously polymerize olefine gases and crack hydrocarbon oils in one stage under high pressure and further polymerize the olefine gases in a separate stage at substantially the same pressure.

A further object of my invention is to provide means for simultaneously degumming under high pressure the combined reaction products from polymerization and cracking zones.

Another object of my invention is to provide means to simultaneously crack gases and hydrocarbon oils, followed by means to separate the gases without material release of pressure, to polymerize the olefines in the separated gases,

and to subsequently treat the reaction products without material release of pressure for the purpose of removing gum, gum-forming bodies and color-imparting bodies.

Another object of this invention is to provide means to simultaneously polymerize olefinic gases and to crack hydrocarbon oils under high pressure in one stage and to simultaneously polymerize olefinic gases and degum the liquid products from the first stage in a second stage without release of pressure.

A further object of this invention is to provide means to use liquid hydrocarbons of intermediate boiling range derived from the products of the process as a solvent to dissolve hydrocarbon gases which it is desired to charge to the process.

Further objects of my invention will be apparent from the following detailed description considered in connection with the accompanying drawing of which the single figure is a diagrammatic elevation of one form of apparatus suitable to the process.

Referring to the drawing, the hydrocarbon oil to be charged to the process is contained in the tank 1 and passes through the pipe 2 into the pump 3 through the pipe 4 and control valve 5 into the upper portion of the vessel 6 wherein a stream of gas is caused to flow counter-current to the downwardly flowing oil and partially absorbed therein. The hydrocarbon oil now bearing gases in solution passes out of the vessel 6 at the bottom through the pipe 7 into the pump 8. The pump 8 raises the pressure of the charge to the degree necessary for the process and forces the liquid through the pipe 9 into the heating coil 10 which is enclosed in a suitable furnace 11. In the coil 10 the temperature of the reactants is raised sufficiently to cause cracking of the hydrocarbon oil and polymerization of the olefines contained therein which were absorbed from the gas introduced into the vessel 6. If the gases dissolved in the oil in vessel 6 are primarily paraffinic, the temperature in coil 10 should be sufficiently high in order to cause cracking of the gases. The reactants leave the coil 10 through the pipe 12 and are cooled by a spray of fluid injected at the point 13. This is preferably an untreated gasoline or light hydrocarbon oil which contains gum or gum-forming and color-producing bodies which it is desirable to remove. The cooling fluid is contained in tank 14 and is pumped by pump 15 through line 16 and control valve 17 to the point 13. The partially cooled reactants pass through the valve 18 in line 12 into the fractionating tower 21 wherein the hydro-

gasoline or light hydrocarbon oil which contains gum or gum-forming and color-producing bodies which it is desirable to remove. The cooling fluid is contained in tank 14 and is pumped by pump 15 through line 16 and control valve 17 to the point 13. The partially cooled reactants pass through the valve 18 in line 12 into the fractionating tower 21 wherein the hydro-

carbons normally liquid are separated from the gases without substantial reduction of pressure. This separation is facilitated by spraying a cooling liquid of the same nature as that used at point 13 into the upper portion of the tower through the line 23 and the control valve 24. The gas leaves the tower 21 through the pipe 25 and passes into the heat exchanger 26, then through pipe 27 and control valve 28 into the heating coil 30. Since the heat input required in the coil 30 is considerably less than that which is required in the coil 10, the coil 30 may be preferably placed in the convection or cooler section of the furnace. The gas leaves the heating coil 30 through the pipe 32 and passes into the reaction zone 35 at a temperature sufficiently high to cause further polymerization at a pressure not materially reduced. To assist in controlling the temperature of the gases, a portion thereof may be by-passed around heating coil 30 through by-pass line 34 and control valve 36. The reaction zone 35 may take any convenient form such as a chamber suitably insulated to prevent heat losses and which may or may not contain catalyst. The reaction zone may be lined on the inside with heat-resisting refractory material such as fire brick or refractory clay and the like, which may be of a composition or be impregnated with substances calculated to have a catalytic effect to promote the polymerization of the reacting gases. The reaction zone may be filled with catalyst in a granular or porous form, or the catalyst may be supported upon a suitable vehicle. The products of the reaction zone 35 pass into the pipe 37 and through valve 38. Cooling fluid which may be of the same nature as that used at the point 13 and at the top of the fractionating tower 21, may be introduced through pipe 39 and control valve 40 into the line 37 at point 41. The mixture passes through the pipe 42 into a reaction zone 44 for the purpose of removing gum, gum-forming and color-imparting bodies. The hot liquid hydrocarbons that are normally liquid leave the fractionating tower 21 through the line 46 and pass through heat exchanger 26 in which part of their heat is given up to the gases from the top of the tower. The liquid leaves the heat exchanger 26 through the pipe 48 and control valve 49, and enters the pipe 42 commingling with the reaction products from zone 35. The zone 44 which may be any suitable chamber, preferably heat insulated, contains an adsorptive catalyst such as fuller's earth or similar material designed to cause polymerization of undesirable gum and gum-forming bodies and also color-imparting bodies. These bodies will be changed to higher boiling compounds which may be easily separated from liquids boiling within the gasoline range. The reactants leave zone 44 through the pipe 50 and control valve 52 where a considerable reduction in pressure takes place. The reactants continue through pipe 50 and enter the fractionating tower 55 preferably at a point intermediate the top and bottom thereof. Liquids having a boiling range above that of gasoline are withdrawn from the fractionating tower through pipe 57 and control valve 58. The normally gaseous hydrocarbons and those boiling within the gasoline range leave the tower as vapor through the pipe 59 and pass into the cooler and condenser 61, then through the pipe 63 into separator 65. Liquids boiling within the gasoline range may be withdrawn through the pipe 67 and control valve 68 while the gases leave the separator at the top through

the pipe 69. The gases are compressed by the compressor 71 and passed through the pipe 72, cooler and condenser 74, pipe 76, into separator 77. The pressure in the separator 77 is sufficiently high to condense gasoline fractions which are carried as vapor in the gas. These fractions may be withdrawn through pipe 78 and control valve 79. The dry gas leaves the top of the separator 77 through the pipe 81 and control valve 82 and passes out of the system. 5

As an alternative the dry gas may pass through line 81 to line 83 through control valve 85 and be returned to the vessel 6 for reabsorption in the hydrocarbon oils. At a point intermediate between the top and the bottom of the fractionating tower 55, a condensate having a boiling range for the most part higher than that of gasoline, may be withdrawn as a side stream through the pipe 92 and control valve 94 to the cooler 95 and through the pipe 96 into the accumulator tank 97. The oil may be withdrawn from accumulator 97 through the control valve 98 and the line 99 by the pump 100 which forces the oil through pipe 102 and valve 103 into the top of the vessel 6, thereby returning it to the process as recycle 20 stock. Gas under a suitable pressure may be introduced from an extraneous source into the bottom of vessel 6 through the line 105 and control valve 106 for solution in the hydrocarbon oil. The olefines in the gas will be selectively dissolved 30 and gases with the highest vapor pressure, such as hydrogen, methane and ethane, which are unsuitable to the process, will remain undissolved and leave the system from the top of vessel 6 through pipe 107 and control valve 108. 35

When the gas charged to the process consists primarily of olefines comprising butylene, propylene and ethylene, the conditions prevalent in the coil 10 may cause sufficient polymerization to avoid necessity for subsequent polymerization in the reaction zone 35. In such cases the invention provides that the reactants leaving the coil 10 through pipe 12 may enter the by-pass pipe 109 and pass through the control valve 110 directly into the pipe 42 and the reaction zone 44. In 45 this case the temperatures in zone 44 will be carried higher than heretofore in order to simultaneously remove the gum, color- and gum-forming bodies from the hydrocarbons boiling within the gasoline range and cause additional polymerization of the olefinic gases. 50

The gas to be processed by my invention may consist of a mixture of hydrocarbons such as are produced in the cracking of hydrocarbon oil or gas, or the stabilization of cracked distillate, or 55 from other oil processing operations yielding gases containing ethylene, propylene and/or butylene. Gases produced from the distillation of coal containing olefines may also be employed. Oils suitable for process are any hydrocarbon distillates heavier than gasoline, and low octane naphthas whose initial boiling point is above substantially 200° F. 60

In carrying out my invention, gases containing from 10% to 100% olefines may be used. The 65 condition however under which the process is operated will vary considerably with the composition of the gas charged. The type of oil which is used as a solvent will also depend to some extent on the character of the gas to be processed. 70 When the gas from an extraneous source is rich in olefines and comprises for the most part butylene, propylene and to a lesser extent ethylene, with the balance a mixture of paraffins and hydrogen, gas oils, mineral seal oils, or heavy hy- 75

drocarbon distillates, will be suitable solvents. Gas oil and the like have selective solvent properties in favor of the olefinic gases. The temperatures at which these gases can be polymerized are also suitable for the cracking of the gas oil. When the gas to be charged from an extraneous source comprises butane, propane, ethane, methane and hydrogen with only a comparatively small percentage of olefines, a low octane naphtha will be the more suitable solvent. The naphtha will tend to dissolve the constituent of the gas having the lowest vapor pressure, namely, butane and propane. The low octane naphtha and paraffinic gases require a higher temperature for processing than the gas oil and olefine gases. The operation in the coil 10 will be primarily cracking in this case with less polymerization.

In accordance with my invention the apparatus may be operated over a range of pressure and temperature conditions to meet the requirements of the type of charge. The gas may be introduced from an extraneous source into the vessel 6 under pressure ranging from 100 to 300 pounds per square inch. The gases having the highest vapor pressure and which are least desirable to the process are not dissolved and leave the system at the top of vessel 6 through pipe 101 and control valve 108. The hydrocarbon solvents may be discharged from the pump 3 into the vessel 6. The solution obtained under atmospheric temperatures more or less in vessel 6 will be discharged by the pump 8 under a pressure of from 500 to 1500 pounds per square inch, and may be heated in the coil 10 to a temperature ranging from 800° to 1200° F. Temperatures of this order may be sustained for a period ranging from 0.5 to 10 minutes. The reactants may then be cooled to a temperature below conversion temperature, preferably 600° to 800° F. by the introduction of a cooling liquid spray and passed into the fractionating tower 21 where by virtue of an additional cooling spray introduced at the top, the gases may be separated and leave at the top of the tower at a temperature of 200° to 350° F. substantially free of fractions boiling within the gasoline range. The gases passing through the heat exchanger 26 may be heated to 400° to 600° F. and further heated to 500° to 1000° F. in passing through the coil 30. At this range of temperature and at a pressure not materially reduced from the charging pressure, except for natural pressure drops through the apparatus, the gases enter the zone 35 undergoing treatment therein over a period ranging from 0.25 to 10 minutes. The reactants leaving reaction zone 35 are cooled by another cooling spray before entering the line 42 wherein they are admixed with the liquid from the bottom of the fractionating tower 21. The liquid from fractionating tower 21 has been partially cooled by passing through the heat exchanger 26 and the temperature to which the reactants from reaction zone 35 are cooled is sufficient to insure a temperature of between 450° to 650° F. for the mixture in pipe 42 and entering the reaction zone 44. In passing through the control valve 49 the liquid from the fractionator tower is reduced in pressure sufficiently to allow the reactants from zone 35 to enter the line 42. The pressure in zone 44 may range from 400 to 1400 pounds per square inch and the time of reaction from 1 to 30 minutes. The mixture of all the products from reaction zone 44 enters the fractionating tower 55 at a pressure reduced to

between slightly super-atmospheric and 100 pounds per square inch. A suitable temperature gradient is maintained from the top to the bottom of the tower 55 so that only hydrocarbons within the gasoline boiling range and gases are permitted to pass from the top of the tower as vapor. After cooling the separation of the gas and hydrocarbons is effected in separator 65. The gas then enters the compressor 71 and is increased in pressure to 100 to 300 pounds per square inch. The compressed gas is cooled and enters the separator 77 wherein remaining gasoline fractions are separated and the dry gas may be eliminated from the system or returned to the vessel 6.

In the event where the gases charged to the system are mainly olefines comprising butylene, propylene and ethylene, the gas and liquid separation provided for by the invention in fractionating tower 21 and the subsequent treatment of the gases in the reaction zone 35 may be omitted. In this case the conditions obtaining in coil 10 will be sufficient to cause polymerization of this type of highly reactive charge. The temperature in coil 10 will preferably be between 800° and 1050° F. In this case the reactants, after the introduction of the cooling spray, may be conducted by a by-pass pipe directly into the zone 44. The zone 44 will in this case be carried under a temperature ranging from 500° to 800° F. and will be used for the purpose of simultaneously polymerizing olefinic gases and for the treatment of gum, gum-forming and color-forming bodies to facilitate their subsequent removal from the hydrocarbon liquids. The pressure in the zone 44 may be somewhat higher than under the previous condition since the pressure drop encountered in zone 35 will have been eliminated. This pressure will be from 500 to 1500 pounds per square inch. After the reactants leave the zone 44 the process is operated in the same manner as described previously.

Although the invention is designed to maintain charging pressure throughout the cracking, polymerizing, and degumming and decolorizing zones, it will be understood that pressures may be dropped somewhat in various parts of the system within the ranges of pressure disclosed.

What I claim is:

1. A method for simultaneously cracking hydrocarbon oil and converting hydrocarbon gases to heavier hydrocarbons such as gasoline which comprises absorbing said gases in said oil, heating the oil and absorbed gases to a temperature sufficient to cause said cracking and converting while under a relatively high super-atmospheric pressure, cooling the resulting products to a temperature below conversion temperature but above the normal vaporizing temperature of gasoline, separating normally gaseous hydrocarbons from the normally liquid hydrocarbons, further heating the normally gaseous hydrocarbons to a temperature sufficient to convert a substantial portion thereof to heavier hydrocarbons, cooling the reaction products to a temperature sufficiently low to prevent further conversion, commingling said normally liquid hydrocarbons with said reaction products and contacting them with adsorptive catalyst at a temperature above the vaporizing temperature of gasoline, all without materially reducing the pressure on the system, and separating the normally gaseous products from the normally liquid products subsequent to contact with said catalyst.

2. Method in accordance with claim 1 in which the oil and absorbed gas is heated to a tempera-

ture of approximately 800° to 1200° F. under pressures of approximately 500 to 1500 pounds per square inch.

3. Method in accordance with claim 1 in which the oil has a boiling range above that of gasoline and the absorbed gases are chiefly olefinic, and the oil with its absorbed gas is heated to a temperature of approximately 800° to 1050° F. under pressures of approximately 500 to 1500 pounds per square inch.

4. Method in accordance with claim 1 in which the oil is of the order of heavy naphtha and the absorbed gases are mainly paraffinic, and the oil with its absorbed gas is heated to a temperature above 1000° F. under pressures of approximately 500 to 1500 pounds per square inch.

5. Method in accordance with claim 1 in which the commingled products are fractionated after contact with the adsorptive catalyst in order to obtain a condensate having a higher boiling range than gasoline, and the condensate is utilized to absorb the gases in the initial step of the process.

6. A method for cracking hydrocarbon oil and for converting gaseous hydrocarbons into higher boiling hydrocarbons which comprises heating said oil and gas in the same stream to a temperature sufficient to cause cracking and conversion under pressure in excess of 500 pounds per square inch, subjecting the oil and gases to said conditions of temperature and pressure for a sufficient period of time to bring about the desired amount of cracking, separating the reaction products into liquids and gases at substantially reaction pressure, subjecting the resulting gases in a separate zone to suitable temperature, without material reduction in pressure, for converting further quantities thereof to higher boiling hydrocarbons, commingling the products from the last mentioned conversion with said liquids, and separating the normally gaseous from the liquid hydrocarbons resulting from the process.

7. Method in accordance with claim 6 in which the commingled products are treated to produce finished gasoline.

8. Method in accordance with claim 6 in which the gases are absorbed in the oil prior to the heating step.

9. Method for simultaneously cracking hydrocarbon oil and converting hydrocarbon gases into liquid hydrocarbons which comprises passing a stream of said oil and gases through a heating and reaction zone wherein the gases are heated to suitable conversion temperatures under high super-atmospheric pressure, cooling the products leaving said zone to a temperature sufficient to substantially arrest conversion, separating the normally liquid from the normally gaseous reaction products, subjecting the normally gaseous products to additional reaction in a separate zone in order to convert further quantities of said

gas into liquid hydrocarbons and thereafter combining the reaction products from the last mentioned conversion with said normally liquid products, contacting the commingled products with solid adsorptive catalyst, and separating the gaseous from the liquid reaction products after treatment with said catalyst.

10. The method of simultaneously cracking hydrocarbon oil and converting hydrocarbon gases to liquid hydrocarbons which comprises subjecting the said oil and gases to elevated temperatures sufficient to cause conversion of said gases into liquids under high super-atmospheric pressure in a conversion zone, cooling the reaction products to a temperature sufficiently low to substantially arrest conversion, separating the reaction products into normally liquid and normally gaseous fractions, subjecting said gaseous fraction to conversion in a second zone whereby to convert substantial portions thereof into liquid hydrocarbons and thereafter admixing the products from said last mentioned conversion with said normally liquid fractions, and contacting the admixed products with an adsorptive polymerizing catalyst, all without substantial reduction of pressure, fractionating the products subsequent to said catalyst treatment in order to separate the normally liquid from the normally gaseous fractions, eliminating the lighter portions from said last mentioned gaseous fraction, and recycling the heavier portions of said last mentioned gaseous fractions to said first mentioned conversion zone.

11. A method for simultaneously cracking hydrocarbon oil and converting hydrocarbon gases to heavier hydrocarbons such as gasoline, which comprises absorbing said gases in said oil, heating the oil and absorbed gases to a temperature sufficient to cause said cracking and converting while under high super-atmospheric pressure, cooling the resulting products to a temperature below conversion temperature but above the normal vaporizing temperature of gasoline, separating normally gaseous hydrocarbons from the normally liquid hydrocarbons, contacting the separated gaseous hydrocarbons in a reaction zone at temperatures of 500°-1000° F. with a polymerizing catalyst in order to effect additional conversion of gas to gasoline, all while under high super-atmospheric pressure, and separating gasoline boiling constituents from the reaction products of the process.

12. Method in accordance with claim 11 in which conversion products from the catalytic step are commingled with said normally liquid hydrocarbons and the commingled products subjected to refining at elevated temperature with catalytic clay prior to separating the gasoline boiling constituents from the products of the process.

PERCY A. MASCHWITZ.
